O. WILLAERT

Des. 158,032

GAME BOARD

Filed Nov. 24, 1948

FIG. 1.

INVENTOR:

BY Oscar Willaert,
Louis Hayka
ATTORNEY.

UNITED STATES PATENT OFFICE

158,032

GAME BOARD

Oscar Willaert, Detroit, Mich.

Application November 24, 1948, Serial No. 149,811

Term of patent 7 years

(Cl. D34—5)

To all whom it may concern:

Be it known that I, Oscar Willaert, a citizen of the United States, and resident of the city of Detroit, county of Wayne, and State of Michigan, have invented a new, original, and ornamental Design for a Game Board, of which the following is a specification, reference being had to the accompanying drawings, forming part thereof.

I claim:

The ornamental design for a game board, as shown.

OSCAR WILLAERT.
